UNITED STATES PATENT OFFICE.

REGINALD KIRSHAW PIERSON AND THOMAS SMITH DUNCAN, OF WESTMINSTER, LONDON, ENGLAND, ASSIGNEES TO VICKERS LIMITED, OF WESTMINSTER, ENGLAND, A BRITISH COMPANY.

ALIGHTING OR LANDING GEAR FOR AIRCRAFT.

1,399,990.

Specification of Letters Patent. Patented Dec. 13, 1921.

Application filed June 21, 1921, Serial No. 479,309. Carved out of application on which Patent No. 1,364,518 was granted January 4, 1921, and filed after grant of patent.

To all whom it may concern:

Be it known that we, REGINALD KIRSHAW PIERSON and THOMAS SMITH DUNCAN, both subjects of the King of Great Britain, residing at Vickers House, Broadway, Westminster, in the county of London, England, have invented certain new and useful Improvements in or Relating to Alighting or Landing Gears for Aircraft, (for which I have filed an application in England, #154,657, July 29, 1919,) of which the following is a specification.

This invention relates to aircraft and has particular reference to seaplanes or hydro-aeroplanes of the flying boat type.

According to this invention we provide improved landing gear for the above type of aircraft in which the wheels are mounted on angularly movable frames and we provide improved means for imparting angular movement to the said frames and also improved means for preventing unrequired movement of the said frames.

In order that the said invention may be clearly understood and readily carried into effect, the same will now be described more fully with reference to the accompanying drawings, in which:—

Figure 1 is a transverse sectional view through the hull or fuselage of a flying boat showing one construction of the improved landing gear partly in section at one side and in dot and pick lines at the other side.

Fig. 2 is a fragmentary side view.

Figs. 3 and 4 are enlarged detail views. A represents the hull of the flying boat. B, B represent the frames at the sides of the hull carrying the landing wheels C, and D represents the transverse operating shaft positioned within the hull; as shown in Fig. 1 the sides of the hull are inclined outwardly toward the keel. Each frame B comprises two parallel tubes whose upper ends are united by a bridge piece B' which is angularly movable with the frame tubes B on a pin forming part of a bracket B³ secured to the side of the hull. The lower ends of the frame tubes are united by a bridge piece or the like B² which as shown at B^{2x} in Figs. 1 and 3 is shaped to fit on or engage with a quadrant E to prevent lateral or sidewise movement of the frame carrying the landing

wheel. The axle C' of each landing wheel is supported in a carrier C² slidably mounted on the two frame tubes B of each frame and formed or provided with an upward extension C³ adapted to slide in a guide forming part of a cross member F' which is rigidly fixed in the two frame tubes B. The upper end of the extension C³ carries a cross member F² similar to the cross member F' but slideable on the two frame tubes B; around the ends of the two cross members F', F² elastic strands F are wound so that when the carrier is moved upwardly relatively to the tube due to a landing shock its movement is resisted and the shock absorbed by the elastic strands; any suitable form of shock absorber such as oleo-pneumatic devices or metal springs with or without dashpots or brakes may be used.

The transverse operating shaft D is connected at its ends to short spindles G by means of universal joints G', which spindles extend at right angles through the hull sides in suitable bearings co-axially with the pivots B³ on which the frames B are angularly movable. The outer end of each short spindle is provided with a worm G² which engages with a worm wheel G³ secured to the upper end of a rod G⁴ rotatably supported in bearings on the frame B and projecting at its lower end into a socket formed on the part B². The lower end of the rod G⁴ carries a toothed wheel G⁵, the teeth of which are in the form of rounded pegs which are adapted to engage with holes E² in the quadrant E secured to the side of the hull. The transverse operating shaft D may be rotated by chain and sprocket gearing which is actuated by the pilot by means of a rotary hand wheel which rotates a large sprocket wheel connected by a chain to a small sprocket wheel G⁶ on one of the spindles G. The rotation of this sprocket wheel G⁶ effects the rotary movement of the shaft and the other spindle G so that the worms G² and worm wheels G³ at the sides of the hull are operated simultaneously for enabling the rods G⁴ and the toothed wheels G⁵ thereon to rotate together so that the toothed wheels will travel along the quadrants by engaging with the holes E² formed therein thereby angularly moving the two

frames B at the same time. During the angular movement of the frames each worm wheel is partially revolved around the axis of the worm in mesh with the latter and 5 owing to the worm gearing the frames are automatically retained against unrequired movement in any angular position to which they may be adjusted. Each quadrant E may be connected to the bracket portion B³ 10 by metal strips E³ which may be secured to the sides of the hull.

At the lower part of the hull an adjustable tie rod H extends between the two sides at points adjacent to the lower parts of the 15 quadrants. The shock absorbers F may be inclosed in stream-line casings as shown for example at F³ in Figs. 1 and 2.

What we claim and desire to secure by Letters Patent of the United States is:—

20 1. In an aircraft, the combination with a hull, of angularly movable wheel carrying frames, operating means carried by each frame and engaging a quadrant on said hull and means for imparting motion to said operating means to angularly move the frame.

25 2. In an aircraft, the combination with a hull, of angularly movable wheel carrying frames, quadrants with which the lower ends of said frames engage, the quadrants having notches, teeth or the like, gear wheels mounted in said frames, means for rotating said gear wheels and a transverse operating shaft operatively connected to said means.

30 3. In an aircraft, the combination with a hull, of angularly movable wheel carrying frames, quadrants with which the lower ends of the frames engage, gear wheels carried by said frames and engaging notches or holes in said quadrants, rotatable rods supported in said frames and connected to said gear wheels, means for rotating said rods and means for causing the frames to be held 35 against unrequired angular movement.

35 4. In an aircraft, the combination with a hull, of angularly movable wheel carrying frames, quadrants at the sides of said hull, engaged by said frames, rotatable rods mounted in said frames carrying at their lower ends, gear wheels for engaging with 40 said quadrants, worm gearing at the upper end of each rod and a transverse operating shaft for imparting movement to the worm gearing to rotate the said rods and the gear wheel so as to impart angular movement to 45 said frames.

50 5. In an aircraft, the combination with a hull, of angularly movable wheel carrying frames pivoted on brackets extending from the sides of said hull, quadrants on said hull, 55 lugs on said frames for engaging with said quadrants, rotatable rods carried by said frames and having gear wheels for engaging with the quadrants, worm gearing at the upper ends of said rods, a transverse operating shaft connected to said worm gearing,

6. In an aircraft, the combination with a hull, of angularly movable wheel carrying frames, quadrants on said hull engaged by the lower ends of said frames, rotatable rods carried by said frames and having gear 70 wheels for engaging with said quadrants, worm wheels at the upper ends of said rods engaged by worms on spindles connected to a transverse operating shaft.

7. In an aircraft, the combination with a hull, of angularly movable wheel carrying frames pivoted at their upper ends on brackets extending from the sides of the hull, such frames being parallel with the sides of the hull and comprising parallel tubes on which 80 a slideable wheel carrier is mounted to co-operate with a shock absorber, quadrants on said hull, lugs on said frames engaging with the quadrants, a rotatable rod supported in each frame and carrying a gear wheel engaging with notches in the adjacent quadrant, and a worm wheel at the upper end of said rod engaged by a worm, the axis of which is in alignment with the axis of rotation of the wheel carrying frames, a spindle 85 carrying said worm wheel and an operating shaft connected to said spindle.

8. In an aircraft the combination with a hull, of angularly movable wheel carrying frames pivoted at their upper ends at the 95 sides of the hull, quadrants with which the lower ends of the frames engage, means on said frames disposed in position for engaging with the quadrants substantially in alignment with the axis of the wheel, a transverse operating shaft, and means whereby 100 said frames may be operated from said shaft, which means serve also to retain the frames against unrequired angular movement.

9. In an aircraft, the combination with a 105 hull, of angularly movable wheel carrying frames pivotally mounted at the sides of the hull, means for swinging the frames to operative and inoperative positions, quadrants on the hull with which the lower ends of the 110 frames engage, means on said frames for engaging with the quadrant at points substantially in alignment with the axes of the wheels engaging with said quadrants to angularly move said frames and means for 115 retaining the frames against unrequired angular movement.

10. In an aircraft, the combination with a hull, of angularly movable wheel carrying frames, slideable members on said frames 120 adapted to carry the wheels and to co-operate with shock absorbers connected to said frames, quadrants with which the lower ends of said frames engage, lugs on said frames and provided with grooves for enabling 125 them to be slidably fitted to said quadrants and to prevent lateral movement of said frames, a transverse operating shaft and means whereby said frames may be operated from said shaft.

11. In an aircraft, the combination with a hull, of angularly movable wheel carrying frames each comprising parallel members having attached thereto a cross bar, a slideable member on said frame carrying the

quadrants with which the lower ends of said frames engage and means for engaging said quadrants to impart angular movement to said frames.

5 wheel supporting axle and a cross bar, elastic strands surrounding said cross bars,

REGINALD KIRSHAW PIERSON.
THOMAS SMITH DUNCAN.
